(57) CLAIM

The ornamental design for a humidifier reservoir lid for positive airway pressure delivery console, as shown and described.

DESCRIPTION

FIG. 1 is a perspective view, from the front, right corner, of a humidifier reservoir lid for positive airway pressure delivery console showing an embodiment according to our new ornamental design;

FIG. 2 is right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is another perspective view thereof;

FIG. 9 is a perspective view, from the front, right corner, of a humidifier reservoir lid for positive airway pressure delivery console showing an embodiment according to our new ornamental design;

FIG. 10 is right side view thereof;

FIG. 11 is a left side view thereof;

FIG. 12 is a top view thereof;

FIG. 13 is a bottom view thereof;

FIG. 14 is a front view thereof;

FIG. 15 is a rear view thereof; and,

FIG. 16 is another perspective view thereof.

In the drawings, the broken lines are for the purpose of illustrating environment only and form no part of the claimed design.

One or more views (e.g., the bottom view) may be omitted and therefore does not form a part of the claimed design.
